CHARLES A. DEMLING, OF NEW YORK, N. Y.

Letters Patent No. 60,862, dated January 1, 1867.

TARGET FOR AIR-GUNS.

The Schedule referred to in these Letters Patent and making part of the same.

TO ALL WHOM IT MAY CONCERN:

Be it known that I, CHARLES A. DEMLING, in the city, county, and State of New York, have invented a new and useful Improved Target for Air-Guns; and I do hereby declare that the following is a full, clear, and exact description thereof, which will enable others skilled in the art to make and use the same, reference being had to the accompanying drawing, forming a part of this specification, in which—

Figure 1 represents a front view of my improved target.

Figure 2 is a vertical cross-section of the same.

Similar letters of reference indicate like parts.

The object of this invention is to construct a target for practising with air-guns in such a manner that such portions of the same as may be struck by the ball will fall back, so as to be out of reach of the shooter. But when all the parts have been thus thrown back they may at once be brought forward again by only pulling a rope at the foot of the target.

The invention consists in attaching a long iron rod to an upright post which is about thirty feet high, and in securing the different parts which constitute the target, and which may be of any desired shape, to the said bar in such a manner that they may swing freely around its centre, and in attaching stationary supports to the bar, against which the parts of the target lean while being aimed at. But when struck they all fall against a rod, which is also hinged to the main bar, and is kept back by weights or spiral springs, and which, when pulled forward by a rope hanging down to the ground, will at once replace all of the target parts to their original position.

The post, A, which is firmly secured in the ground, supports, by two or more arms, a, the round horizontal bar, B. The target consists of small divisions, C, which can be made of steel, brass, wood, India rubber, or any suitable material whatever, and which may have the shape of little birds, stars, flowers, or any other desired design. Each of these divisions is hinged on the bar B, so that it can swing free and independent of the others around the same. When in position to be fired at, the divisions lean forward, as shown in fig. 2, and rest against a wire rail, d, which is stationary on the bar B. When struck, each division falls back against the wire railing, e, as shown in red lines in fig. 2. This rail e swings on the bar B, and is held back by spiral or other springs, f, or by weights, as may be deemed best. When all the divisions have been struck, or when all want to be brought back to their original position, it is only necessary to pull on the rope, g, which, being attached to a forward extension, h, of the rail e, will throw the said rail forward and with it each one of the divisions C leaning on it. In this manner a target of great height can always be made ready for firing again in the shortest time and without any difficulty.

This target is constructed mainly for use with air-guns, especially the one invented by me, a description of which is contained in my application for a patent therefor, now on file in the Patent Office.

Having thus described my invention, I claim, and desire to secure by Letters Patent—

Dividing a target into a series of parts C, each of which is acted upon separately by the ball or projectile, but all of which are readjusted at the same time by a combination of the rail e, springs or weights f, and rope g, with the bar B, rails d, and post A, substantially in the manner and for the purpose herein specified.

The above specification of my invention signed by me this 31st day of July, 1866.

CHARLES A. DEMLING.
